UNITED STATES PATENT OFFICE.

S. G. MONCE, OF BRISTOL, CONNECTICUT.

IMPROVEMENT IN TOOLS FOR CUTTING GLASS.

Specification forming part of Letters Patent No. 91,150, dated June 8, 1869.

To all whom it may concern:

Be it known that I, S. G. MONCE, of Bristol, in the county of Hartford and State of Connecticut, have invented a new and Improved Tool for Cutting Glass; and I do hereby declare that the following is a full, clear, and exact description thereof, reference being had to the accompanying drawings, making a part of the same, in which—

Figure 1 is a front elevation of my invention. Fig. 2 is a side elevation of the same. Fig. 3 is a front elevation of the cutter. Fig. 4 is a side elevation of the same.

Similar letters of reference indicate like parts.

My invention consists in the use or employment of a revolving steel roller, the periphery of which roller is beveled on both sides, so as to form a cutting-edge, and is fitted to revolve in a suitable frame, and attached to a handle for operating the same.

The cutter A is made from steel, and is turned smooth and round, and afterward hardened. The sides *a a* are parallel, or nearly so, for a short distance, and then beveled toward each other, so as to meet about midway between the same, thus forming the point or cutting-edge D. The beveled portion *c c* of the sides *a a* should be at an angle of about forty-five degrees to the axis of the cutter A, and, consequently, will be at near right angles to each other.

It is not necessary that the angles of the beveled sides *c c* should be at exactly right angles to each other; but near that angle, or a very little more obtuse, the cutter is found to operate to the best advantage.

The cutter A can be fitted to revolve on a pin, or on solid journals at each end, which latter mode I prefer, and show the same in the drawings.

B designates the frame, which can be made either in one piece or in halves, and secured by a rivet or screw. In the drawing it is made of two pieces, and secured by a rivet. The frame B, near one end, is provided with bearings for the journals *d d*, which journals should be a little shorter than the thickness

of the sides *e e* of the frame B, in order that when the sides *e e* are placed against a straight-edge or other gage, the end of the journal shall not come in contact with such gage. The handle C can be of any desired form, and secured to the frame B in any proper manner. I construct said handle like the handle ordinarily used for a diamond-tool.

To cut glass or like substances, the cutter A is drawn quickly across the glass, pressing upon it at the same time, which causes the cutter to revolve. A fine line or scratch is made in the path of the cutting-point D, similar to that made by a diamond.

As the general form of the tool, except the cutter, is the same as an ordinary diamond-tool, the same gages and devices can be employed to cut the glass into any desired pattern.

In cutting circular work from glass, it is customary to fix a diamond in a suitable machine, so that a circle can be readily described. For similar uses I dispense with the described handle C and frame B, while the cutter A can be fitted to revolve in any desired part of the machine.

By my invention I produce a tool for cutting glass which is equally convenient in use as an ordinary diamond, and can be sold, at a large profit, for one-tenth of the usual cost of a diamond. It requires less skill to operate it, and can be used by different persons without any liability to injure the same.

I do not claim, simply, a revolving cutter; but

What I claim as new, and desire to secure by Letters Patent, is—

1. The cutter A, constructed substantially as shown and described, and for the purposes set forth.

2. The combination of the cutter A, frame B, and handle C, substantially as and for the purposes described.

S. G. MONCE.
